Albion D. T. Libby

ATTORNEY

UNITED STATES PATENT OFFICE.

CLAUDE J. HOLSLAG, OF SOUTH ORANGE, NEW JERSEY, ASSIGNOR TO ELECTRIC ARC CUTTING & WELDING COMPANY, OF NEWARK, NEW JERSEY.

METALLIC ARC CUTTING AND WELDING APPARATUS.

Application filed September 20, 1920. Serial No. 411,658.

To all whom it may concern:

Be it known that I, CLAUDE J. HOLSLAG, a citizen of the United States, residing at South Orange, in the county of Essex, State 5 of New Jersey, have invented certain new and useful Improvements in Metallic Arc Cutting and Welding Apparatus, of which the following is a description, reference being had to the accompanying drawing and 10 to the figures of reference marked thereon.

In my Patent 1,305,363 granted to me June 3, 1919, I have shown and described various transformers suitable for metallic arc cutting and welding apparatus and have 15 claimed therein, in particular, a transformer of this type provided with adjustable flux regulating means for varying the inductive effects of the windings of the transformer.

20 The present application is directed specifically to the form of invention disclosed in Fig. 4 of said patent.

It has been found that an alternating current system which utilizes alternating current at the welding arc, possesses many advantages over the direct current arc and in certain classes of work it is desirable to have a voltage, at the instant of starting the arc, considerably higher than the voltage 25 required to maintain the arc after it has been started, but in some cases it is desirable to reduce this open circuit voltage previous to starting the arc so that the operator will not get any serious shocks, should 30 he accidentally come in contact with the exposed electrodes.

It is an object of this invention to provide a transformer which will have a comparatively low open circuit voltage previous to 40 striking the arc.

Other objects will be apparent to those skilled in the art after reading the specification and claims.

In the accompanying drawing, 1 indicates 45 a transformer having three legs 2, 3 and 4 of which the leg 4 is much smaller in cross-section than the other two. Wound about the leg 2 are two windings: a primary winding 5 provided with a multiplicity of taps 6, and a main secondary winding 7. The main secondary winding is connected at one end to an electrode 8 and at the other end to a stabilizer or a steady turn or turns 9 wound about the yoke of the transformer.

55 The stabilizer in turn is connected to an

auxiliary secondary winding 10 wound about the middle leg 3 of the transformer and the latter winding is connected to a voltage regulating coil 11 on the leg 4, said last named coil being wound in opposition 60 to the auxiliary secondary winding. It is of course understood that the coil 11 may be made in sections connected to one another in series and provided with suitable taps. The free end of the voltage regulating coil 65 is connected to the remaining electrode 12.

In the primary circuit is bridged a fan motor 13 driving a blower 14 which during the operation of the transformer serves to cool the same. 70

Bridged across the main and auxiliary secondary windings is a non-inductive resistance in the form of a lamp 15 which serves the double function of assisting in absorbing the kick voltage of the secondary circuit 75 when the arc is broken and which also serves as a pilot light to indicate that current is flowing in the secondary circuit after the primary switch has been closed, thus telling the operator that the welding electrode, 80 usually carried in a handle, is "alive" and ready.

Shunting the leg 3 is a permeable member 16 which may be inserted into or out of the transformer, at will, to shunt more 85 or less of the flux through the auxiliary secondary winding and the auxiliary regulating coil and thus obtain closer regulation of the circuit. This member of course is not essential to the operation of the transformer, but its presence is desirable. 90

Taps 17 on the voltage regulating coil 11 are provided to vary the open circuit voltage of the secondary. The leg 4 may be placed on one side of leg 2 and core 3 on its 95 other side or leg 4 may be placed between legs 2 and 3.

With the primary circuit closed and with the electrodes separated, the primary coil 5 sets up a flux threading the coils 7, 9, 10 100 and 11, the voltage of the coils 7, 9 and 10 being in phase on open circuit. The coil 11, however, opposing the remaining coils subtracts its voltage from that of the others and as a result, if the electrode terminals 105 be accidentally touched, no appreciable shock will be felt. The core 4 is however easily saturated and the instant any appreciable current passes therethrough as by striking the arc at the electrodes, it becomes ineffect- 110

- tive to exercise any detrimental restraining influence on the voltage; for then the flux produced by coils 5 and 10 predominates greatly over the flux produced by the coil 11 and thereby the leg 4 together with its coil 11 practically becomes eliminated from the magnetic circuit so far as the welding operations are concerned. During the welding operation of the transformer, the voltages of the coils 9 and 10 shift in phase with respect to the voltage in the coil 7 and with each other and the resulting and total operating voltage is therefore less than the open circuit voltage.
- 15 Having thus described my invention what I claim is:
1. An apparatus for metallic arc cutting and welding including a transformer having a three legged core, a primary winding wound on one core leg and a multi-part secondary wound with a part on each of the legs and all connected in series with each other and in circuit with arc cutting and welding electrodes.
  2. An apparatus for metallic arc cutting and welding including a transformer having a three legged core, a primary winding wound on one core leg and a multi-part secondary wound with a part on each of the legs, one of the parts opposing the others and all connected in series with each other and in circuit with arc cutting and welding electrodes.
  3. An apparatus for metallic arc cutting and welding including a transformer having a three legged core, one of the core legs being much smaller in cross section than the others, a primary winding wound on one core leg and a multi-part secondary wound with a part on each of the legs and all connected in series with each other and in circuit with arc cutting and welding electrodes.
  4. An apparatus for metallic arc cutting and welding including a transformer having a three legged core, one of the core legs being much smaller in cross section than the others, a primary winding wound on one core leg and a multi-part secondary wound with a part on each of the legs, one of the parts opposing the other and all connected in series with each other and in circuit with arc cutting and welding electrodes.
  5. An apparatus for metallic arc cutting and welding including a transformer having a three legged core, one of the core legs being much smaller in cross section than the others, a primary winding wound on one core leg and a multi-part secondary wound with a part on each of the legs, one of the parts opposing the others, taps on said opposing portion and all connected in series with each other and in circuit with arc cutting and welding electrodes.
  6. An electric arc welding system com-

prising a transformer having primary and secondary windings, a plurality of electrodes connected to the secondary winding and an auxiliary winding connected in series with one of the windings.

7. An electric arc welding system comprising a transformer having primary and secondary windings, a plurality of electrodes connected to the secondary winding and an auxiliary winding connected in series with the secondary winding.

8. An arc welding system comprising a transformer including a core member, primary and secondary windings mounted thereon, a plurality of auxiliary windings mounted upon the core member and so connected to the secondary winding as to be automatically excluded from the main magnetic circuit when current is flowing in the secondary winding and a plurality of electrodes connected in the secondary circuit.

9. An arc welding system comprising a transformer including a core member, primary and secondary windings mounted thereon, a plurality of stationary auxiliary windings so mounted upon the core member and connected to the secondary winding as to be automatically excluded from the main magnetic circuit when current is flowing in the secondary winding and a plurality of electrodes connected in the secondary circuit.

10. An arc welding system comprising a transformer including a core member, primary and secondary windings mounted thereon, a plurality of auxiliary windings mounted upon the core member and connected to the secondary winding as to be excluded from the main magnetic circuit when current is flowing in the secondary winding and a plurality of electrodes connected in the secondary circuit.

11. An arc welding system comprising a transformer including a core member, primary and secondary windings mounted thereon, a plurality of stationary auxiliary windings so mounted upon the core member and connected to the secondary winding as to be excluded from the main magnetic circuit when current is flowing in the secondary winding and a plurality of electrodes connected in the secondary circuit.

12. An arc welding system comprising a transformer including a core member, primary and secondary windings mounted thereon, an auxiliary winding so mounted upon the core member and connected to the secondary winding as to be excluded from the main magnetic circuit when current is flowing in the secondary winding and a plurality of electrodes connected in the secondary circuit.

13. An arc welding system comprising a transformer including a core member, primary and secondary windings mounted

thereon, an auxiliary stationary winding so mounted upon the core member and connected to the secondary winding as to be excluded from the main magnetic circuit 5 when current is flowing in the secondary winding and a plurality of electrodes connected in the secondary circuit.

14. An apparatus for metallic arc cutting and welding including a transformer having 10 a three legged core, a primary winding on one core leg, a part of the secondary on the same core leg with the primary and another part of the secondary on a second leg of the transformer and a further part of the secondary 15 on the third leg of the transformer, which latter leg acts as a magnetic shunt to the second mentioned part of the secondary.

15. An apparatus for metallic arc cutting and welding including a transformer having 20 a three legged core, a primary winding on one leg of the core, a main secondary winding on the same leg as the primary, an auxiliary part of the secondary winding on another leg of the core and a regulating winding 25 on the third leg of the transformer, the main secondary, auxiliary secondary and

regulating winding all being connected in series.

16. An apparatus for metallic arc cutting and welding including a transformer having 30 a three legged core, a primary winding on one core leg and a multi-part secondary wound with a part on each of the legs and all connected in series with each other and in circuit with arc cutting and welding electrodes, the winding on one of said leg portions acting under load to set up a flux in a direction acting to prevent a substantial amount of the flux set up by the primary 35 from entering said leg portion. 40

17. An apparatus for metallic arc cutting and welding including a transformer having 45 a plurality of core legs, a primary winding and a part of the secondary winding on one core leg, another part of the secondary on another core leg, and a third portion of the secondary on another core leg, which latter core leg is in permanent shunt relation to the second mentioned core leg.

In testimony whereof, I affix my signature.

CLAUDE J. HOLSLAG.
